[57] CLAIM

The ornamental design for a combined toy wagon and animals therefor, as shown and described.

DESCRIPTION

FIG. 1 is a perspective view of a combined toy wagon and animals therefor showing our new design;

FIG. 2 is another perspective view thereof showing the animals outside the wagon;

FIG. 3 is a right side elevational view thereof;

FIG. 4 is a top plan view thereof;

FIG. 5 is a bottom plan view thereof;

FIG. 6 is a front elevational view of each of the elements comprising our design;

FIG. 7 is a rear elevational view thereof;

FIG. 8 is a top plan view of the design as arranged in FIG. 1;

FIG. 9 is a right side elevational view thereof;

FIG. 10 is a front elevational view thereof;

FIG. 11 is a left side elevational view thereof; and

FIG. 12 is a rear elevational view thereof.
